UNITED STATES PATENT OFFICE.

GEORGE SNYDER SIMPSON, OF MORGANTOWN, WEST VIRGINIA.

THERMOSTATIC HEAT OR FIRE ALARM.

1,074,654.

Specification of Letters Patent.

Patented Oct. 7, 1913.

Application filed May 23, 1912. Serial No. 699,204.

To all whom it may concern:

Be it known that I, GEORGE SNYDER SIMPSON, a citizen of the United States, residing at Morgantown, in the county of Monongalia and State of West Virginia, have invented new and useful Improvements in Thermostatic Heat or Fire Alarms, of which the following is a specification.

This invention relates to improvements in 10 thermostatic heat or fire alarms of that general type which embodies an expansible body and a circuit closer operated thereby.

The object of the invention is to provide a 15 simple and compact construction of the type referred to, which shall be sensitive and reliable in its action, and in which the parts are readily accessible for any purposes desired.

An embodiment of the invention is illustrated in the accompanying drawings, wherein:

Figure 1 is a side elevation, partly in longitudinal section; and Fig. 2 is a section on the line 2—2 of Fig. 1.

Similar characters of reference designate corresponding parts throughout the several views.

The operating parts are mounted upon a suitable base 1 which is to be attached to a 30 wall and may be of any desired form. The base 1 may carry any suitable contact device, for example and preferably, a push button device, comprehending the contacts 2 and 3 and the push button 4, by which the contact 35 3 may be engaged with the contact 2. The base 1 also forms an anchorage for supporting posts 5, four of which are preferably employed. The posts 5 project perpendicularly from said base and pass through openings in plates 6 and 7. The plate 6 is determinately spaced from the base by sleeves 8 which surround the posts 5, and the plate 7 is similarly spaced from the plate 6 by sleeves 9.

The plate 6 forms a guide for an axially projecting stem 10 which is provided at the inner end of an expansible body, indicated generally at 11, and the plate 7 forms an anchorage for said body at the outer end 50 thereof. The body 11 is preferably made up of separable sections and, in the instance disclosed, comprises inner and outer cup-like heads 12 and 13, and intermediate sections

14. The stem 10 is carried by the head 12. The sections 14 are similar in construction 55 and any desired number of them may be employed. Two of these sections are shown and each comprises cup-like members 15 and 16 and an axial tube 17 connecting said member. The member 15 is of slightly greater 60 diameter than the member 16 and receives the adjacent cup-like part in closely fitting telescoping relation. The head 12 fits within the member 15 of one section and the member 16 of the same section fits within the 65 member 15 of the next section, and the member 16 of the latter fits within the head 13. The engagement of the interfitting cup-like members is sufficiently close to be effectually air tight, yet it does not interfere with the 70 ready expansion or distention of the body 11 when the latter is subjected to heat.

The body 11 may be directly connected to the plate 7. It is preferred, however, to provide said body with a swiveled adjusting 75 screw 18 which is threaded through a central opening in the plate 7 and by means of which a preliminary adjustment of the position of the body 11, with reference to the button 4 or to the contact 3, may be made. In this 80 way it is possible to set the device to operate when the heat has reached some determined degree. The stem 10 passes through a central opening 19 of the plate 6 and is in line with, and, in most instances, in contact with, 85 the button 4 which it forces inwardly when the body 11 expands.

The alarm device may be of any suitable character. An electric bell 20 is shown, which is wired in the usual way to the contacts 2 and 3.

Having fully described my invention, I claim:

A device of the type set forth, comprising a base having contacts associated therewith and a push button for operating one of the contacts, a plurality of posts projecting from the base, a pair of plates mounted in spaced relation on the posts, one of the plates being intermediate the other plate and the base 100 and having an opening, an expansible body arranged between the plates and including cup-like end heads located adjacent the plates and sections intermediate said heads and each including cup-like members and connecting tubes, the adjacent cup-like parts

having telescopically interfitting relation, the cup-like end head adjacent the inner plate having a stem which projects through the opening of said plate for engagement with said push button, the other cup-like end head being anchored to the outer plate.

5 In testimony whereof I have hereunto set

my hand in presence of two subscribing witnesses.

10 GEORGE SNYDER SIMPSON.
